COLLAPSIBLE BOX OR DISPLAY DEVICE

Frederick Herbert Lowe, Thorpe, Chertsey,
EnglandApplication July 18, 1939, Serial No. 285,161
In Great Britain December 12, 1938

4 Claims. (Cl. 229—16)

This invention relates to a collapsible box and to a cardboard or like blank from which the box is constructed.

The object of the invention is to provide an improved or simplified construction of collapsible box or display device of the type provided with a bottom, front, back and side walls and two lateral flaps or panels for display purposes standing in the plane of the front of the box.

According to the invention, a box provided with a bottom, front, back and side walls and lateral flaps or panels as aforesaid is constructed from a single blank which comprises a part adapted to form the back wall of the box and two lateral wings adapted to fold into the planes of the sides of the box and provided with extensions to form the aforementioned flaps or panels, the front wall of the box being formed by a part which is cut out of one of the aforesaid lateral wings so that it remains attached to that wing by means of the aforesaid extension thereof and is brought forward with that extension when the wings are folded into the planes of the sides of the box. The bottom of the box is formed by a third wing which proceeds from the part cut out from one of the first mentioned wings as aforesaid and is bent back when the said cut out part is brought forward. The third mentioned wing has two lateral extensions adapted to be folded so as to lie against the side walls of the box when erected and one of these lateral extensions serves to cover the opening which would otherwise be left at one side by reason of the part cut out therefrom to form the front wall of the box as aforesaid. The third mentioned wing may also have an extension adapted to be folded so as to lie flat against the back wall of the box when erected. The blank may also be provided with a fourth wing for display purposes proceeding from the top edge of the part which forms the back of the box. This wing may stand in the same plane as the back of the box when erected or it may be folded forwards or backwards as may be desired.

The invention is illustrated in the accompanying drawings in which:

Figure 1 is a plan of a blank,

Figure 2 is a front elevation of a box made from the blank shown in Figure 1.

Figure 3 is a side elevation of the same box,

Figures 4 and 5 are a plan and edge view respectively of the box shown in Figures 2 and 3 when collapsed,

Figure 6 is a view similar to Figure 1 showing a slightly modified form of blank, and

Figure 7 is a side elevation of a box made from the blank shown in Figure 6.

The blank shown in Figure 1 consists of a single piece of cardboard or other suitable material cut from a flat sheet. It comprises a part 1 adapted to form the back wall of the box, and two lateral wings 2 and 3 adapted to fold into the planes of the sides of the box and provided with two lateral extensions 4 and 5 intended to form flaps or panels for display purposes.

In order to form a front wall for the box, a cut is made along the line 6 so as to cut out from the parts 1 and 3 a front wall part 7 having a tab 7a which part 7 remains attached to the rest of the wing 3 by means of the extension 5 thereof. The blank has a third wing 8 which extends downwards from the part 7, this part 8 being intended to form the bottom of the box. Two lateral extensions or flaps 9 and 10 and a downward extension or flap 11 proceed from the wing 8 as shown. A fourth wing 12 which proceeds from the top edge of the part 1 is provided for display purposes.

The blank is intended to be folded along the lines shown as broken lines in Figure 1 and the blank may be treated in any known manner to facilitate folding along these lines.

For the purpose of making a box from the blank shown in Figure 1 it is necessary to attach the front wall part 7 to the wing 2. To enable this to be done, the wing 2 may be folded upon the part 1 so as to bring the fold line between the parts 2 and 4 upon the fold line at which the tab 7a is attached to the part 7. The tab may then be fastened to the part 2 by means of staples 13 (Figure 4). This may be done as part of the process of manufacture of the blank.

In Figure 5, the part 7 is shown displaced somewhat from the plane of the part 1 and the part 4 is shown folded back upon the part 2. This is done merely for clearness of illustration, however, and in practice the part 7 may remain in the same plane as the parts 1 and 3 and the part 4 may lie flat upon the parts 1 and 3 so that there will not be more than two thicknesses of material at any part of the folded blank. The completed blanks may be packed in this condition.

When the box is to be erected, the part 7 is pulled forwards so that the parts 2 and 3 are pulled into the planes of the sides of the box. The part 8 is then folded back to form the bottom of the box, the flaps 9, 10 and 11 being tucked up inside the box. The flaps 10 and 11 serve to cover the opening which would otherwise be

left at one side of the box and at the back of the box by reason of the fact that the front wall part 7 is cut out from the back and side wall parts 1 and 3.

The blank shown in Figure 6 of the drawings is generally similar to that shown in Figure 1 and corresponding parts are marked with the same reference numerals. The difference between the form of blank shown in Figure 6 and that shown in Figure 1 is in the fastening means provided for attaching the front wall part 7 to the part 2. In the form shown in Figure 6, the front wall part 7 is formed with a tab 7b and a slit 7c is formed at the foldline between the parts 2 and 4 so that the tab 7b can be pushed through the slit 7c. The tab is formed with ears 7d and suitable slits 7e are formed in the part 2 of the blank to receive these ears.

The tab 7b and the slits 7c and 7e form a releasable fastening which can easily be fastened by the user when the box is erected. There is therefore no need to bring the parts 2 and 7 together until the box is to be used. The blank shown in Figure 6 may therefore be laid out flat as shown in Figure 6 for transit and storage.

The blank shown in Figure 6 is erected to form a box in the same manner as that shown in Figures 4 and 5 except that the fastening of the parts 2 and 7 together is carried out as part of the process of erecting the box. For this purpose, the tab 7b is pushed through the slit 7c and the ears 7d are then tucked into the slits 7e as shown in Figure 7.

The shape of the line 6 along which the part 7 is cut out may be varied as desired so as to give the front wall of the box a straight top edge or an edge of decorative shape such as that illustrated in the drawings. The parts 4, 5 and 12 may also be cut to decorative shapes as may be desired.

The boxes shown in the drawings are of greater width than depth from front to back and consequently the cut-out part 7 necessarily extends into the back wall part 1. In some cases, however, the depth of the box from front to back may be so much greater than the width of the

box that the front part 7 is cut out of the side wall part 3 only, the back wall part 1 being left intact.

I claim:

- 5 1. A cardboard or like blank adapted to form a box, consisting of a single piece of material cut from a flat sheet and comprising a part to form the back wall of the box, two lateral wings foldable into planes to form the side walls of the box and provided with extensions to form lateral flaps at the front of the box, a part partially cut out of a portion of the blank which includes at least one of said lateral wings and along a line which defines two edges of the front wall but leaves said cut-out part attached to said lateral wing along a line which joins the latter to the extension thereof, said cut-out part being foldable along its line of attachment to said lateral wing into a forward plane to form the front wall of the box when the lateral wings are folded relatively to the back wall forming part into the planes of the sides of the box, a third wing attached to said cut-out part and bendable backwardly to form the bottom of the box, and extension means on said third wing foldable upwardly within the box to cover the opening left therein by removal of said cut-out part.
- 10 2. A blank according to claim 1, wherein said cut-out front wall forming part is formed with a tab for fastening it to one of said side wall forming lateral wings.
- 15 3. A blank according to claim 1, wherein said cut-out front wall forming part is formed with a tab, and the blank has a slit cut therein adjacent to one of said side wall forming lateral wings to receive said tab and thereby fasten the front wall forming part releasably to the respective side wall forming wing.
- 20 4. A collapsible box made from a blank according to claim 1, wherein said front wall forming part is permanently fastened to both side wall forming wings, one of said side wall forming wings being stapled to said front wall forming part.
- 25

FREDERICK HERBERT LOWE.
